UNITED STATES PATENT OFFICE.

JACOB W. ELVYN AND EDWARD A. CHRISTOPH, OF CHICAGO, ILLINOIS.

COIN-RECEPTACLE.

1,152,937.

Specification of Letters Patent.

Patented Sept. 7, 1915.

Application filed May 14, 1915. Serial No. 27,985.

To all whom it may concern:

Be it known that we, JACOB W. ELVYN and EDWARD A. CHRISTOPH, citizens of the United States, residing at Chicago, in the 5 county of Cook and State of Illinois, have invented a certain new and useful Improvement in Coin-Receptacles, of which the following is a full, clear, concise, and exact description, reference being had to the accompanying drawings, forming a part of this 10 specification.

Our invention relates to coin receptacles and is particularly concerned with such a receptacle primarily in the form of an envelop, which may be conveniently carried in 15 one's pocket.

It is the object of our invention to provide improved means whereby the insertion of coins is permitted, but whereby the extraction of coins, without destroying the envelop, is extremely difficult, if not impossible.

It is a further object of our invention to provide means whereby such a coin receptacle as above described may conveniently be mailed to persons, means being provided for addressing the envelop without in any way defacing the appearance of the envelop or the printing which may be thereon. 25 Thus, we provide an improved slot guard and also an extension of one of the walls of the envelop, which may be folded back over the face of the envelop and held in place by convenient means, to which our invention 30 more specifically relates, and upon which extension the address of the person for whom the envelop is intended may be written.

Referring to the accompanying drawings: 40 Figure 1 shows a perspective view of the cut blank which forms the envelop of our invention before it is glued together. Fig. 2 is a longitudinal sectional view with the extension not held upon the face of the envelop. Fig. 3 is a sectional view showing the manner in which the said extension is held upon the face of the envelop; and, Fig. 4 is a face view of the envelop showing the extension folded back thereon, the line 3-3 45 indicating the plane upon which the sections of Figs. 2 and 3 are taken, the direction being indicated by the arrows.

The device preferably is formed of heavy 55 paper, pasteboard, or cardboard, and comprises the front wall 5, and the rear wall 6 joined to the front wall 5 at the line 7. At

the top of each wall a flap is provided, the flap 8 of the wall 5 being provided with a slot 9, and the flap 10 of the wall 6 being cut at 11-11 to form a secondary flap 12. 60 The wall 6 carries the flap 13 upon its free side, and the flap 14 upon the bottom. The wall 5 is provided with the extension 15 at the bottom, this extension being of substantially the same over-all size as the wall 5 65 itself. As illustrated, the wall 5 is provided with an opening or slot 16, which registers with the slot 9 in the flap 8.

Glue is disposed upon the flap 13, the flap 14 and the flap 10, around the secondary flap 12, and the parts are folded together as illustrated in Fig. 2, so as to form a complete enclosure. In this folding process the secondary flap 12 is passed through the slot 9 but not through the slot 16; it is then passed 75 downwardly, all as illustrated in Fig. 2.

It will be apparent that if a coin is inserted through the slot 16 it can readily be pushed downwardly between the secondary flap 12 and the wall 5, and that it will be 80 practically impossible for the coin to be extracted through the opening 16, since, if the envelop were inverted, the coins would undoubtedly be caught upon the lower end of the secondary flap 12, or the lower end of the 85 flap 8. Since the coin cannot be extracted through the opening 16, the only way in which it can be removed from the envelop is by destroying the envelop.

As illustrated, the connection between the 90 extension 15 and the wall 5 is scored at 17. The free end of the extension 15 is cut as illustrated at 18-18 to provide a central flap 19, which, as illustrated in Fig. 3, may be inserted through the slots 16 and 9 and 95 passed upwardly therethrough so as to hold the extension 15 firmly down upon the face of the wall 5. This extension 15 may be provided with lines for an address, and in any event forms a blank surface which, 100 when addressed, will have the appearance of an ordinary addressed envelop. The recipient can remove the extension from the envelop and retain the envelop for the use which has been described.

What we claim as new and desire to secure by Letters Patent of the United States is:

1. In a coin container, a front wall and a back wall each having a flap extending 110 downwardly therefrom, one of said flaps having an opening therein and the other

having a secondary flap extending therefrom, said main flaps being secured together, with said secondary flap extending through said opening, and an opening in one 5 of said walls above the bottom of said flaps.

2. In a coin container, a front wall and a back wall each having a flap extending downwardly therefrom, one of said flaps having an opening therein and the other 10 having a secondary flap extending therefrom, said main flaps being secured together, with said secondary flap extending through said opening, and an opening in one of said walls above the bottom of said flaps, the remaining edges of said walls being secured together. 15

3. In a coin container, a front wall and a back wall each having a flap extending downwardly therefrom, one of said flaps 20 having an opening therein and the other having a secondary flap extending therefrom, said main flaps being secured together, with said secondary flap extending through said opening, and an opening in one of said walls registering with the opening in said flap. 25

4. In a coin container, a front wall and a back wall each having a flap extending therefrom, the flap on said front wall hav-

ing an opening therein, and the other flap 30 having a secondary flap extending therefrom, said main flaps being secured together, with the secondary flap extending through said opening, and an opening in the front 35 wall registering with the opening in said flap, the remaining edges of said walls being secured together.

5. In a coin container, an envelop having a slot therein near one end thereof for the entry of coins, and an extension hinged to the opposite end of said envelop, the free 40 end of said extension having a tongue insertible in said slot to hold said extension in position folded back upon the face of said envelop. 45

6. In a coin container, an envelop having a slot therein near one end thereof for the entry of coins, and an extension hinged to the opposite end of said envelop, the free 50 end of said flap having two longitudinal incisions to form a central tongue insertible in said slot to hold said extension in position folded back upon the face of said envelop.

In witness whereof, we hereunto subscribe our names this 10th day of May, A. D. 1915. 55

JACOB W. ELVYN.
EDWARD A. CHRISTOPH.
